(57) CLAIM

The ornamental design for a cabinet with charging drawer, as shown and described.

DESCRIPTION

FIG. 1 is a front view of the cabinet with charging drawer; and,

FIG. 2 is a right side view of the cabinet of FIG. 1. The left side view is a mirror image of the right side view. Shading is provided to show contour and not surface ornamentation. The broken lines are for illustrative purposes only and form no part of the claimed design.
